UNITED STATES PATENT OFFICE.

CLARENCE F. COLBERT, OF HOOPESTON, ILLINOIS.

TIPPING-MACHINE.

1,111,006.

Specification of Letters Patent.

Patented Sept. 22, 1914.

Application filed May 9, 1912. Serial No. 696,080.

To all whom it may concern:

Be it known that I, CLARENCE F. COLBERT, a resident of Hoopeston, in the county of Vermilion and State of Illinois, have invented certain new and useful Improvements in Tipping-Machines, of which the following is a full, clear, and exact description.

The invention relates to tipping machines, 10 for closing the vent-perforations in the tops of cans or the caps thereon.

One object of the invention is to provide an improved tipping machine which is adapted for rapid operation so that it is capable 15 of tipping a large number of cans.

Another object of the invention is to provide an improved tipping machine which is simple in construction and efficient in operation.

20 Another object of the invention is to provide improved tipping devices in which the soldering point is surrounded by a gas chamber and is heated from the outside thereof to effectively and uniformly heat the point, 25 to render it efficient in soldering.

Lastly the invention designs to provide a tipping machine of improved construction and operation.

The invention consists in the several novel 30 features hereinafter set forth and more particularly defined by claims at the conclusion hereof.

In the drawings: Figure 1 is a front elevation of a machine embodying the invention. Fig. 2 is a vertical section taken on line 35 2-2 of Fig. 1. Fig. 3 is a horizontal section taken on line 3-3 of Fig. 1. Fig. 4 is a detail plan, parts being shown in the section, of the solder-feeding device. Fig. 5 is a 40 front view of the solder-feeding device. Fig. 6 is a section taken on line 6-6 of Fig. 4. Fig. 7 is a front view of the track for guiding the tipping devices, the carrying arms for said devices being shown in the track.

45 Fig. 8 is a vertical section through the tipping device carrier showing the chamber for supplying gas to the tipping devices. Fig. 9 is a detail section of one of the tipping points and its carrying arm. Fig. 10 is a 50 plan view of one of the tipping devices. Fig. 11 is a section taken on line 11-11 of Fig. 9. Fig. 12 is a detail of the lock for the jacket around the soldering point.

The machine is adapted to close the vent 55 holes in cans α which are moved in a longi-

tudinal plane by the endless carrier b which is provided with pins c for engaging the cans. Carrier b is operated by an endless chain d , in manner well understood in the art, and travels upon tracks e which are sustained in any suitable manner. 60

The supporting structure of the tipping machines comprises a bracket 15 which is adapted to be secured to the tracks e , by a clamp 16 and bolt 17, posts 18 which are secured in said bracket, and a cross-head 19 extending between and secured to the upper ends of said posts. Guide bars 20 between which the cans are guided against transverse movement to keep them alined 70 with the rotating tipping devices are each adjustably sustained by a pair of arms 21 and 22 extending forwardly and rearwardly from said bars respectively. The outer end of each of these arms is adjustably secured 75 to a post on a lug 23 on bracket 15, by a screw 24, and its inner end is pivoted, as at 25, to one of the guide-bars 20. The purpose of this guiding-means is to permit both bars to be adjusted to guide cans of different 80 sizes without varying the center of the longitudinal travel of the cans relatively to the tipping devices, and so that lateral adjustment of the tipping devices will not be necessary. By providing a pair of parallel arms 85 for each bar 20, the latter will always be adjusted in parallel relation to the plane of travel of the cans.

A frame 27 is slidably mounted on posts 18, being provided with sleeves 28 through 90 which the posts extend, and this frame is vertically adjustable on said posts by a screw 29 which extends through the cross-head 19 and is provided with a hand-wheel 30 whereby it may be turned. The reduced 95 lower end 31 is rotatable in a bearing 32 in said frame which is held between a shoulder on the screw and a collar 33, so that the frame will be raised or lowered by turning the screw. 100

The machine comprises a vertically rotatable series of tipping-devices which are adapted to successively contact with the cans on conveyer b . All of these devices are mounted on and carried by a carrier in the 105 form of a hollow spider 34, which is secured by a screw 35 to a sleeve 36 which is journaled in a bearing 37 on vertically adjustable frame 27. This sleeve is provided with a fixed collar 38 which is held by a flanged 110

collar 39 which is secured to bearing 37, so that the sleeve will be rotatable and be held against longitudinal movement, in its bearing. The outer end of this sleeve 36 is open and connects with a chamber 40 in bearing 37 and pipes 41 and 42 connected to said chamber supply gas and air to form the fuel for heating the tipping-points, which fuel passes through sleeve 36 to the chambers 43 in the arms of carrier or spider 34.

Each tipping-device is rotatably supported in one of the arms 44 of carrier 34 by a spindle 45 which is tapered and extends through a correspondingly tapered seat in said arm, to form an air-tight pivotal joint between the spindle 45 and said arm. Each spindle 45 has a port 46 therein which connects with the chamber 43 in arm 44 by a port 47. To the front end of each spindle 45, is adjustably secured by a screw 50, the hub 48 of an arm 49 which carries a tipping device at its outer end.

Each tipping device comprises a hollow shell or jacket 51 and a soldering point 52 which is secured in the shell, extends through the chamber in the shell and has a tapered terminal 53 which is adapted to contact with a strip of solder and deposit it in the vent opening of the can. The fuel from port 46 in spindle 45 passes through a port 53^a in arm 49, under control of a regulating screw 54 whereby the flow of fuel may be varied. Shell 51 comprises a removable section 55 provided with a handle 56, and a lug 57, adapted to fit into a recess in a lug 58 formed on the section of the shell which is integral with arm 49. A latch 59 is pivoted to a lug 60 and is adapted to engage a lug 61 on shell-section 55 to hold the sections together. By removing section 55, access may be had to the soldering point 52 for cleaning or replacement. An opening 60^a is formed between the tapered terminal 53 of point 52 and the jacket, for the burning of the fuel and escape of the products of combustion. Fuel will be constantly supplied to all of the soldering devices rotating with the carrier 34. Each spindle 45 which carries one of the tipping-devices is pivotally movable in the carrier. The purpose of this pivotal movement is to permit each soldering point in the lower arc of its rotation to remain in contact with the cans, by gravity, while the can-tops are moving in a horizontal plane and the soldering devices are moving in a vertical plane. Resultantly, the soldering points may remain in contact with the can a sufficient period to effectively close the vent openings, while the cans are traveling in a rectilinear path and the soldering-devices are operated by the vertically rotating carrier. An arm 62 is secured to the inner end of each spindle 45 and carries a roller 62^a adapted to travel in annular track 63 which is formed in frame 27. This track

is normally disposed to cause the soldering-points to contact with the cans before they reach the vertical center and so that after contacting with the can, the soldering devices will be free to remain in contact with the can by gravity until the tipping-operation has been completed, and for that purpose, a straight portion 64 is formed adjacent the lower portion of the track to release the soldering devices and permit their rollers 62^a to be lifted off of the outer flange of the track by the cans. After each device has completed a tipping-operation, it will be guided against pivotal movement in either direction by the inner and outer flanges of the track. The lower portion of the outer flange of the track serves to limit the movement of the soldering-devices in the event no can is fed thereto.

Continuous rotary movement is imparted to the carrier 34 by gearing comprising a gear-wheel 66 fixed on sleeve 36 by screw 67, a gear-wheel 65 meshing with gear 66 and secured to a vertical shaft 68 which is mounted in a bearing 69 in frame 27 and in bearings 70 and 71 on bracket 15, and a worm-gear 72 through which said shaft extends and which is operatively connected thereto by key 73 and an elongated groove 74 in the shaft. Bearings 70 and 71 confine worm-gear 72 against movement with shaft 68 so that said shaft may be adjusted vertically with the frame 27, key 73 and groove 74 being adapted to maintain operative connection to drive the shaft in its different vertical positions. Worm-gear 72 is driven by a worm-pinion 75 on a shaft 77 which is journaled in bearings 76 on bracket 15 and to which movement is imparted in synchronism with the conveyer 6 to cause the speed of the tipping-devices to correspond to the movement of the cans. Resultantly the carrier for the tipping-devices will be constantly driven, one of said devices being adapted to tip each can as it passes thereunder. This mechanism thus exemplifies a tipping-machine in which there is a series of vertically rotating tipping devices adapted to successively engage the cans and which is adapted for rapid operation. The machine also exemplifies one in which tipping-devices may be continuously rotated.

A device is provided for feeding solder into the path of the rotating tipping-points to cause the solder to be fed each time that the tipping-point removes its end portion. Since the carrier and tipping-devices are constantly operated whether or not a can is present beneath the tipping-devices the solder feed is controlled by the cans so that if no can is passing beneath the tipping-devices, no solder will be fed to the point and in this manner, the necessity of providing can-controlled driving mechanism for the solder feed arises. This solder-feeding

device comprises a pair of rolls 80 and 81, the former of which is grooved and knurled to firmly grip a strip of solder α and force it through a tube 82^a which is secured in a guide-lug 82 on the frame 27. Step-by-step movement is imparted to roll 80, which is journaled upon a stud 83 secured in frame 27, by a pawl 84 which is pivoted to the end of an arm 85 on a sleeve 86 which is journaled on stud 83 and is provided with a segmental rack 87. A spring 88 is applied to hold pawl 84 in engagement with a ratchet 90 on roll 80. A spring-pressed dog 89 is applied to hold ratchet 90 and roll 80 against retraction. An arm 91 which is secured to a vertical rock-shaft 92 is provided with a rack 93 meshing with rack 87, and shaft 92 is operated to retract pawl 84 by an arm 94 which is adjustably secured 20 to shaft 92 by a clamp 95 and has a cam 96 disposed in the path of travel of the cans, so that arm 91 will be operated to retract pawl 84 only when a can is being fed to the tipping machine. Such retraction 25 brings a roller 97 on the arm 91, into the path of a tappet-wheel 98 which is secured to vertical drive-shaft 68, so that when a can is present on conveyer b it will operate arm 94 to set the solder-feeding devices into position to cause arm 91 to be operated to 30 turn roll 80 and feed solder, by one of the tappets of wheel 98. Each tappet will engage roller 97 and operate the feeding-device to cause the end of the strip of solder 35 to be wiped by the tipping-point just before it passes into engagement with the can which is operating arm 94. Roller 81 is mounted upon an arm 100 which is pivoted to a stud 101 connected to frame 27 and a screw 102 passing through a lug 103 on the frame is adapted to adjust the arm to cause the strip of solder to be firmly gripped between rolls 80 81 and to be fed forwardly thereby. This solder-feeding mechanism 40 thus exemplifies one which is controlled by cans passing to the tipping-devices and whereby solder will be fed to the tipping-devices only when a can is present on the conveyer, and this mechanism is particularly adapted for a tipping machine in 45 which the tipping devices are continuously driven when operated.

The invention is not to be restricted to the details set forth since these may be modified within the scope of the appended claims 55 without departing from the scope and spirit of the invention.

Having thus described the invention, what I claim as new and desire to secure by Letters Patent, is:

1. In a tipping-machine, the combination of a sleeve, a vertically rotating carrier on the sleeve, a series of tipping devices pivotally connected to said carrier to cause them 65 to rotate therewith, means for feeding cans

to said devices, mechanism for feeding solder to the tipping-devices, means for supplying fuel to said sleeve and means for guiding the tipping devices in their rotation, said carrier having ducts therein for conducting fuel from the sleeve to said devices. 70

2. In a tipping machine the combination of a vertically rotatable carrier, a series of tipping devices pivotally mounted to swing vertically on the carrier, means for feeding cans in a longitudinal line to said devices, and mechanism for feeding solder to said devices, the pivotal movement of said devices relatively to the carrier permitting the tipping devices to remain in contact with the cans by gravity during a portion of each revolution of the carrier. 75

3. In a tipping machine the combination of a vertically rotatable carrier, a series of tipping devices pivotally mounted to swing vertically on the carrier, means for feeding cans in a longitudinal line to said devices, means for constantly supplying fuel to said devices, guide means for said devices for a portion of their movement, and mechanism 85 for feeding solder to said devices, the pivotal movement of said devices relatively to the carrier permitting the tipping devices to remain in contact with the cans by gravity during the portion of the revolution of the carrier in which the tipping devices are not 90 guided by the guide means. 95

4. In a tipping machine the combination of a vertically rotatable carrier, a series of tipping devices pivotally mounted to swing vertically on the carrier, means for feeding cans in a longitudinal line to said devices, and mechanism for feeding solder to said devices, the pivotal movement of said devices relatively to the carrier permitting the tipping devices to remain in contact with the cans during a portion of each revolution, and guide means for the tipping devices formed to release them for independent vertical movement by the cans during a part of 100 each revolution. 105

5. In a tipping machine, the combination of a vertically rotatable carrier, a series of tipping devices pivotally mounted to swing vertically on the carrier, means for feeding cans in a longitudinal line to said devices, means for constantly supplying fuel to said devices, mechanism for feeding solder to said devices, the pivotal movement of said devices relatively to the carrier permitting 115 the tipping devices to remain in contact with the cans during a portion of each revolution, and vertical guide means for the tipping devices formed to release them for independent vertical movement by the cans during a part 120 of each revolution. 125

6. In a tipping-machine, the combination of a vertically adjustable frame, a screw for adjusting said frame, a rotatable carrier journaled on said frame, a series of tipping 130

devices pivotally connected to said frame and rotatable therewith, mechanism for rotating the carrier, means for feeding cans to said devices, and means for guiding the tipping devices in their rotation with the carrier.

7. In a tipping-machine, the combination of a vertically adjustable frame, means for conducting fuel to said frame, a vertically rotatable carrier journaled on said frame and having ducts formed therein, a series of tipping-devices pivotally connected to said frame and rotatable therewith, mechanism for rotating the carrier, means for conducting fuel from the ducts in the carrier to said devices, and means for guiding the tipping-devices in their rotation with the carrier.

8. In a tipping-machine, the combination of a vertically adjustable frame, a vertically rotatable carrier journaled in said frame, a series of tipping devices pivotally connected to said carrier and rotatable therewith, mechanism for rotating the carrier, means for feeding cans to said devices, means for guiding the tipping devices in their rotation with the carrier.

9. In a tipping-machine, the combination of a vertically adjustable frame, a vertically rotatable carrier, a sleeve mounted in said frame and on which the carrier is mounted, a series of tipping-devices pivotally connected to said carrier and rotatable therewith, mechanism for rotating the carrier, mechanism for feeding cans to said devices, and means for guiding the tipping-devices in their rotation with the carrier.

10. In a tipping-machine, the combination of a supporting bracket, posts on the bracket, a vertically adjustable frame guided by said posts, a vertically rotatable carrier journaled in said frame, a screw for adjusting said frame to adjust the carrier, a series of tipping-devices pivotally connected to said frame and rotatable therewith, mechanism for rotating the carrier, means for feeding cans to said devices, and means for guiding the tipping-devices in their rotation with the carrier.

11. In a tipping-machine, the combination of a frame, a vertically rotatable carrier journaled on the frame, a series of tipping-devices, arms carrying the tipping-devices, pivotally connected to the carrier, means for guiding said devices in their rotation by the carrier, and means for feeding solder to the tipping devices.

12. In a tipping-machine, the combination of a frame, a vertically rotatable carrier journaled in the frame, a series of tipping-devices, arms carrying the tipping-devices, pivotally connected to the carrier, means for guiding said devices in their rotation by the carrier, said arms having ports therein, means for supplying fuel to the tipping-de-

vices through said ports, and means for feeding solder to the tipping devices.

13. In a tipping-machine, the combination of a frame, a sleeve held in said frame, means for supplying fuel to said sleeve, a vertically rotatable carrier on the sleeve, a series of tipping devices, arms carrying the tipping-devices, pivotally connected to the carrier, means for guiding said devices in their rotation by the carrier, the arms and carrier having ducts therein for conducting fuel from the sleeve to said devices, and means for feeding solder to the tipping-devices.

14. In a tipping-machine, the combination of a vertically rotating carrier, a series of tipping-devices, pivotally connected to the carrier, to swing vertically, mechanism for rotating the carrier, means for feeding cans to said devices, and means for controlling the pivotal movement of the tipping-devices in the carrier, said means being formed to permit the tipping-devices to be swung vertically by a can.

15. In a tipping-machine, the combination of a vertically rotating carrier, a series of tipping-devices pivotally connected to the carrier to swing vertically, mechanism for rotating the carrier, means for feeding cans to said devices, means for controlling the pivotal movement of the tipping devices in the carrier, said means being formed to permit the tipping-devices to be swung vertically by a can, and mechanism for feeding solder to said devices.

16. In a tipping-machine, the combination of a vertically rotating carrier, a series of tipping-devices, arms carrying said devices, pivotally connected to the carrier, to swing vertically, mechanism for rotating the carrier, means for feeding cans to said devices, means for controlling the pivotal movement of the tipping devices in the carrier, said means being formed to permit the tipping-devices to be swung vertically by a can, and mechanism for feeding solder to 110 said devices.

17. In a tipping-machine, the combination of a frame, a carrier rotatably mounted on the frame, mechanism for rotating the carrier, a series of tipping-devices, spindles for said devices pivotally sustained in the carrier, arms on said spindles, a track for guiding said arms to control the pivotal movement of said devices in the carrier, and means for feeding solder to said devices.

18. In a tipping machine, the combination of a frame, a carrier rotatably sustained by the frame, mechanism for rotating the carrier, a series of tipping devices, spindles for said devices pivotally sustained in the carrier and rotating therewith, arms on said spindles, a track for guiding said arms to control the pivotal movement of said de-

- vices in the carrier, and formed to permit the devices to be swung by a can, and means for feeding solder to said devices, said spindles and carriers providing means for respectively supplying fuel to said devices.
19. In a tipping-machine, the combination of a frame, a carrier vertically rotatable on the frame, mechanism for rotating the carrier, spindles pivoted in the carrier, arms at one end of said spindles, a series of tipping-devices secured to said spindles, arms on the other end of spindles, a track for guiding said latter arms to control the pivotal movement of said devices in the carrier, and means for feeding solder to said devices.
20. In a tipping-machine, a tipping device comprising a hollow jacket, a tipping-point secured to and extending through said jacket and having its pointed end projecting therefrom, an opening being formed in the jacket around said pointed end, and means for supplying fuel to said jacket.
21. In a tipping-machine, the combination of means for feeding cans in a longitudinal direction, means for guiding said cans on said feeding means comprising a pair of parallel bars disposed to guide the sides of the cans, a pair of adjustable parallel arms for each of said bars, a series of rotatable tipping-devices, and means for feeding solder to said devices.
22. In a tipping-machine, the combination of an endless carrier for feeding cans in a longitudinal direction, means for guiding said cans comprising a pair of parallel bars between which the cans will be guided, a pair of adjustable parallel arms for each bar, a bracket on which the arms are pivoted, a vertically adjustable frame sustained by said bracket, driving mechanism sustained by the bracket, a carrier rotatably mounted in said frame, a series of tipping-devices pivoted to the carrier, and means for feeding solder to said devices.
23. In a tipping machine, the combination of a vertically rotatable carrier, a series of tipping devices, spindles for said devices pivotally sustained in the carrier and rotating therewith, a swivel joint between said carrier and said spindles, arms on said spindles, tipping points carried by said arms, said carrier, spindles and arms having ducts therein for conducting fuel from the carrier to the tipping points, and distributor plates situated in the apertures of said arms.
